UNITED STATES PATENT OFFICE.

WILLIAM KIRKWOOD, OF FORSYTH, MONTANA.

RAILROAD-TIE.

1,118,291.

Specification of Letters Patent. Patented Nov. 24, 1914.

Application filed November 12, 1912. Serial No. 730,838.

To all whom it may concern:

Be it known that I, WILLIAM KIRKWOOD, a citizen of the United States, residing at Forsyth, in the county of Rosebud and State of Montana, have invented new and useful Improvements in Railroad-Ties, of which the following is a specification.

My invention has special relation to the class of railroad ties wherein specific means are provided for securely holding the rails thereto.

An object of my invention is to provide a device of the above character wherein are provided detachable receiving means for holding the rails in place.

Another object of my invention is to provide a rail tie constructed preferably of concrete thereby reducing the cost and device of this nature to a minimum.

Another object is to provide a concrete tie from which project, at diametrically opposite points pairs of rail supporting members for making a more substantial bed for the rail.

Broadly my invention consists of a tie having a substantially wedge shaped opening provided therein which receives correspondingly formed blocks, the latter being provided with means for receiving fastening members of the rails. Rail supporting members project at diametrically opposite points from the tie so as to form a substantial bed for the rails and by their provision it is apparent that the efficiency of my invention is greatly added to.

With the above and other objects in view, my invention relates to such details of construction and in the arrangement and combination of the several parts as will be hereinafter fully described and specifically pointed out in the appended claim.

In describing my invention in detail reference will be had to the accompanying drawings wherein like characters denote like or corresponding parts throughout the several views, and in which:

Figure 1 is a perspective view of my invention. Fig. 2 is a sectional view taken on line 2—2 of Fig. 1.

In the accompanying drawings, wherein

is illustrated the preferred form of my invention, the numeral 1 designates the tie or body portion of the device which is preferably formed from concrete or a material of the like consistency thereof reducing the cost of manufacture to a minimum. Formed within the tie and at certain distances from the ends thereof are the substantially wedge shaped openings 2 the smaller mouth of which is disposed at the outer face of the tie so that they may receive correspondingly formed blocks 3, the latter having pairs of internally screw threaded openings 4 provided therein for the reception of the fastening members of the rails, not shown. By this arrangement it will be apparent that as the tie is disposed upon a solid base all danger of the blocks working loose is obviated, for they cannot be removed from the upper face of the tie as is apparent.

Rail supporting members 5 project at diametrically opposite points from the tie and adjacent the openings therein, the supporting members of one tie being disposed adjacent or in alinement with the supporting members of the other tie so that a secure and compact basis is provided for the rails.

I desire to lay the greatest of stress upon the simplicity of my invention and it is thought that the advantages and novel features of the same will be readily comprehended from the foregoing disclosure.

I desire it to be understood that I may make slight changes in the construction and in the arrangement and combination of the several parts provided such changes fall within the scope of the subjoined claim.

Having thus fully described my invention what I claim as new, and desire to secure by Letters Patent, is:

A rail tie including a body adapted to extend transversely of the railway, elongated projections extending laterally from the opposite margins of said body and in spaced relation to the opposite ends of the latter, the terminals of said projections adapted to abut the proximate terminals of analogous projections to provide a continuous rail engaging surface, said body provided with openings tapering inwardly

from the lower face of said body to the upper face thereof, said openings being formed in proximity to the opposite ends of said body coincident with the longitudinal axis of said projections, and blocks arranged in said openings and conforming to the contour thereof and adapted for secure-

ment to the rail, said blocks having their opposite faces flush with the opposite faces of said body, substantially as specified.

WILLIAM KIRKWOOD.
